(57) **CLAIM**

The ornamental design for a divot repair tool, as shown and described.

DESCRIPTION

FIG. 1 is an isometric view of a front, top, and right side of an ornamental design for a divot repair tool in a first configuration;

FIG. 2 is an isometric view of a top, rear, and left side of the divot repair tool of FIG. 1;

FIG. 3 is an isometric view of a bottom and rear of the divot repair tool of FIG. 1;

FIG. 4 is a front elevational view of the divot repair tool of FIG. 1;

FIG. 5 is a rear elevational view of the divot repair tool of FIG. 1;

FIG. 6 is a left side elevational view of the divot repair tool of FIG. 1;

FIG. 7 is a right side elevational view of the divot repair tool of FIG. 1;

FIG. 8 is a top plan view of the divot repair tool of FIG. 1; and,

FIG. 9 is a bottom plan view of the divot repair tool of FIG. 1.

The dash-dash-dash broken lines illustrate portions of the divot repair tool that form no part of the claimed design. The dash-dot-dash broken lines illustrate boundary lines and form no part of the claimed design.

1 Claim, 8 Drawing Sheets
